UNITED STATES PATENT OFFICE.

ALBERT JOHN ALCOCK, OF VANCOUVER CITY, CANADA.

DESIGN FOR A LAMP-CHIMNEY.

SPECIFICATION forming part of Design No. 25,870, dated August 4, 1896.

Application filed April 30, 1896. Serial No. 589,781. Term of patent 7 years.

To all whom it may concern:

Be it known that I, ALBERT JOHN ALCOCK, a subject of the Queen of Great Britain, residing at Vancouver city, in the county of Vancouver, in the Province of British Columbia and the Dominion of Canada, have invented a new and original Design for Lamp and Gas Chimneys and Globes, of which the following is a specification.

10 This invention relates to a new and original design for lamp and gas chimneys or globes, and it has for its object to provide a design of this character that shall be both useful and ornamental.

15 The leading feature of the design resides in a lamp and gas chimney or globe compoundly curved in an upward direction from its contracted neck to form at the top a widened annular dished enlargement, having 20 at its edge a peripheral series of approximately vertically-disposed inverted-U-shaped figures bounded by unbroken sigmoidal lines which form widened U-shaped spaces between said figures.

25 In the drawings, Figure 1 is a perspective

view of a lamp-chimney embodying the herein-described design. Fig. 2 is a vertical sectional view thereof.

Referring to the drawings, the numeral 1 designates a lamp and gas chimney or globe 30 compoundly curved in an upward direction from its contracted neck to form at the top a widened annular dished enlargement 2. The dished enlargement 2 is provided at its edge with a peripheral series of approximately 35 vertically-disposed inverted-U-shaped figures 3, bounded by sigmoidal lines 4, which form between the figures 3 widened U-shaped spaces 5.

What I claim is—

40 The design for a lamp and gas chimney or globe herein shown and described.

In testimony that I claim the foregoing as my own I have hereto affixed my signature in the presence of two witnesses.

ALBERT JOHN ALCOCK.
